WEFT END HOLDER FOR WEFT
REPLENISHING LOOMSHerbert A. Whitin, Worcester, Mass., assignor to
Crompton & Knowles Loom Works, Worcester,
Mass., a corporation of Massachusetts

Application November 20, 1943, Serial No. 511,048

10 Claims. (Cl. 139—247)

This invention relates to improvements in weft end holders for weft replenishing looms and it is the general object of the invention to provide a thread holder actuated by a vibration motor which is responsive to vertical as well as horizontal vibration of the loom.

Multicolor weft replenishing looms generally employ a so-called stationary magazine in which are stored stacks of reserve bobbins from which weft ends extend. It is necessary to hold the weft end of each bobbin so that when it is transferred the shuttle will be threaded, but the weft end should be held above the path of the lay to avoid thread breakage. It has been proposed heretofore to provide a thread holder including a pair of meshing gears between which the weft ends extend and drive the gears by a vibration motor including a weight mounted for suspension in a horizontal direction with respect to its carrier and provided with a pawl to actuate a ratchet wheel connected to one of the thread gears. In such thread holders the weight has been mounted so that it could vibrate only in a horizontal direction.

Experience shows that looms do not all vibrate in the same way during operation. In some looms the horizontal vibration is predominant, or at least sufficient to rock the thread holder weight. In other looms, however, the horizontal vibration is negligible but enough vertical vibration is present to operate a thread holder if the latter is made so as to respond to up and down motion. It is an important object of my invention to mount the weight of the thread holder in such a manner as to cause its operation by both horizontal and vertical vibration, or by either kind of vibration acting alone.

It is a further object of my present invention to provide the weight of the thread holder with pawls which can communicate either a vertical or a horizontal movement, or both, from the weight to the feed ratchet connected to the thread gears.

Heretofore the weight has been mounted on a pair of leaf spring supports which hang downwardly and are secured to the ends of the weight and it is for this reason that the weight moves horizontally only. It is another object of my present invention to use only one of these supports for one end of the weight and support the other end of the weight by a spring which permits its vertical motion. The vertical feed pawl is attached to the free end of the weight.

It is a further object of the invention to use horizontal and vertical feed pawls so related

that each may serve as a check pawl to hold the ratchet against retrograde movement when the other pawl is having an idle stroke.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is an end elevation of part of a weft replenishing loom having attached thereto a thread holder made according to my present invention.

Fig. 2 is an end elevation of a thread holder looking in the direction of arrow 2, Fig. 1,

Fig. 3 is a horizontal section on line 3—3 of Fig. 2, and

Fig. 4 is a view of the interior of the thread holder with the dust plate removed and showing the operating mechanism within the thread holder casing.

Referring to the drawing, particularly Figs. 1 and 2 I have shown a loom frame 10 provided with a magazine 11 in which are stored reserve bobbins 12. The magazine is made in usual manner for multicolor weft replenishing looms so that the bobbins are arranged in vertical stacks and weft ends W extend outwardly from the reserve bobbins. The magazine includes in its construction a tie rod 13 on which is mounted an arm 14 having a foot 15 to which is attached a thread holder designated generally at H. The thread holder comprises a box like casing 17 having top, bottom and side walls 18, connected to a web 19. The foot 15 is secured to one of the side walls.

The thread holder has a ratchet wheel 21 within casing 17 secured to a stud 22 rotatable on the web 19 and secured on the other side of 40 the web to a thread engaging gear 24 meshing loosely with a second thread engaging gear 25 mounted for free rotation on a stud 26. The latter is carried by a plate 27 held to the casing in adjusted horizontal position by screws 29 passing through slots 30 in plate 27 and tapped into web 19. When the ratchet wheel 21 is turned counter-clockwise as viewed in Fig. 4 it causes thread gear 24 to turn and the latter in turn causes the other thread gear 25 to turn in 50 such direction that the meshing parts of the gears move downwardly. The weft ends W lie between the gears 24 and 25 and are subjected to a tension to draw them taut with respect to their reserve bobbins by turning of the ratchet wheel 21. If desired an adjusting stop screw 31

passing through one of the vertical walls 18 may be used to limit movement of the vibrating weight to be described hereinafter.

The matter thus far described is of common construction and of itself forms no part of my present invention. During loom operation there is generally sufficient vibration transmitted through the arm 14 to the thread holder H to cause the latter to vibrate both horizontally and vertically. A frictional drag for the gears 24 and 25 is provided in the form of a spring plate 32 located between said gears and web 19, and a thread guard 33 prevents the weft ends W from getting between the gears and the spring plate. For a further understanding of the matter thus far described reference may be had to prior patents to Payne Nos. 1,842,731 and 1,979,765.

In carrying my present invention into effect, I provide a weighted member 40 having the left end thereof as viewed in Fig. 4 suspended on a leaf spring 41 the bottom of which is attached to the weight as at 42, and the top of which is secured to the casing as at 43. The weight is provided with a horizontal pawl 45 which is preferably in the form of a leaf spring held to the left end of the weight at 42 and having the right end thereof in engagement with the ratchet wheel 21.

The right end of weight 40 has secured thereto a second pawl 46 extending upwardly to engage the ratchet 21 and secured to the weight as at 47. There is no suspending member for the right end of the weight similar to the leaf spring 41 for the left end of the weight, but instead I provide a leaf spring 48 which is secured to the right end of the weight 40 and is then bent backwardly and to the left under the weight and in engagement with the bottom wall of the thread holder casing. This spring 48 is sufficiently strong to hold the weight elevated with pawl 45 in engagement with the ratchet 21.

With the thread holder and loom at rest the parts will assume the approximate position shown in Fig. 4 with both the pawls 45 and 46 engaging the ratchet wheel 21 and with the weight held resiliently in raised position by spring 48. The left end of weight 40 can move horizontally but has only a very slight negligible vertical motion, whereas the right end of the weight can move both horizontally and vertically because of the manner of its support. When the loom is in operation the arm 14 and thread holder H vibrate and the weight is capable of a relative movement with respect to the thread holder casing. The vibration is subject to variation depending upon the particular loom to which the thread holder is applied and also the location of the loom on the floor of the weave shed. Some looms are observed to have such a vibration that the casing H has considerable lateral or horizontal but very little vertical motion, while in other looms the vertical vibration is more pronounced than the horizontal. In most looms, however, the casing H is observed to vibrate both vertically and horizontally.

Assuming for the purposes of description that the parts are in the position shown in Fig. 4 at the beginning of loom operation and that the effect of vibration of the loom is to move the casing H to the left as viewed in Fig. 4, the weight 40 because of its inertia will have a relative right hand motion with respect to the thread holder and the pawl 45 will give the ratchet wheel 21 an angular movement in a counter-clockwise direction. If, on the other hand, the first vibration of the thread holder should be down the inertia

of the weight will prevent it from moving downwardly as fast as the case does under forced vibration of the loom operation and the pawl 46 will have a relative upward movement with respect to the ratchet 21 and turn the latter in a counter-clockwise direction as viewed in Fig. 4. If the first movement of the case should be to the right the ratchet wheel 21 would then move away from the left end of weight 40 due to the inertia of the latter and the pawl 45 will take hold of a new tooth on the ratchet wheel. Because of the action of suspending spring 41, however, the weight 40 will ultimately be moved to the right so that the pawl 45 will give the ratchet wheel 21 a partial rotation under these conditions. Similarly, should the first vertical motion of the ratchet 21 be up the pawl 46 will move downwardly relatively to the ratchet wheel to take hold of a new tooth and when the spring 48 subsequently raises the right end of weight 40 the pawl 46 will impart angular movement to the ratchet wheel.

In operation, it is observed that the right end of weight 40 has both a horizontal and vertical motion. Pawl 46 is made of spring material and is preferably so bent that it remains in engagement with the wheel 21 when the weight 40 moves to the right with respect to the thread holder case, and in a similar manner the pawl 45 tends to move upwardly and remain in contact with the ratchet wheel during any slight downward movement which the left end of the weight may experience due to its swinging movement around the support 43. Thus it is that both pawls remain in contact with the ratchet wheel at all times and each pawl serves as a check pawl to prevent retrograde movement of the wheel 21 when the other pawl is having an idle stroke to take hold of a new tooth.

There is some slight friction between the left end of spring 48 and the bottom wall which it engages, but the weight of the member 40 is such that its inertia against horizontal movement will be sufficient to overcome this friction and the spring 48 will slide back and forth on the bottom wall. I have found that in certain settings of the thread holder satisfactory results can be obtained by the use of pawl 46 only. Under these conditions, when pawl 45 is omitted, the free right end of weight 40 has a tendency to rise when the weight moves to the right as viewed in Fig. 4 due probably to the action of spring 48 and the fact that the other end of the weight is suspended from the support 43. The latter under these conditions may be considered as a center around which the weight tends to move and it is for this reason that the pawl 46 alone can be relied upon to turn the ratchet 21. I prefer, however, to use both pawls 45 and 46 since they give assurance that both the horizontal and vertical movement of the weight 40 with respect to the case will impart angular movement to the ratchet wheel.

From the foregoing it will be seen that I have provided a simple support for weight 40 such that one of its ends is free to vibrate vertically as well as horizontally and that this end is provided with a driving pawl for the ratchet 21. It will further be noted that the pawl 45 serves the usual function of turning the ratchet wheel due to horizontal movement of the weight, but in addition serves as a check pawl to prevent retrograde movement of the ratchet when the right end of the weight is moved down relatively to the case so that the pawl 46 can engage a new tooth. It

will further be noted in this last connection that each pawl serves as a check to prevent retrograde movement of the ratchet for the other pawl. Also, the pawl 46 will be acted upon by a force tending to raise it when the weight moves horizontally to the right with respect to the case due to the manner of support of the weight 48.

Having thus described my invention it will be seen that changes and modifications may be made therein by those skilled in the art without departing from the spirit and scope of the invention and I do not wish to be limited to the details herein disclosed, but what I claim is:

1. In a loom thread holder which vibrates horizontally and vertically during loom operation and has a traveling surface to engage reserve bobbin weft ends, a weight supported by the thread holder and mounted for free movement horizontally and vertically relatively to the thread holder due to horizontal and vertical vibration of the thread holder, and feed means for the traveling surface actuated by both horizontal and vertical movement of the weight relatively to the thread holder.

2. In a loom thread holder which vibrates horizontally and vertically during operation of the loom on which the thread holder is mounted, the thread holder having a traveling surface to engage weft ends extending from reserve bobbins in the loom, a weight mounted on said thread holder for both horizontal and vertical free movement relatively to the thread holder due to horizontal and vertical vibration of the latter, and feed means operated by the weight when the latter moves either horizontally or vertically relatively to the thread holder to effect movement of said traveling surface.

3. In a loom thread holder having a support which vibrates horizontally and vertically during loom operation, said support having thereon a traveling surface to engage weft ends extending from reserve bobbins in the loom, a weighted mass having one end suspended from said support for free movement in a horizontal direction relatively to the support due to horizontal vibration of the latter, resilient means on said support to mount the other end of said weighted mass for vertical movement relatively to said support due to vertical vibration of the latter, and feed means for the traveling surface actuated by said weighted mass when the latter moves either horizontally or vertically.

4. In a loom thread holder which vibrates horizontally and vertically during loom operation, the thread holder having a traveling surface to engage weft ends extending from reserve bobbins in the loom, a weight having one end connected to the thread holder and mounted for free horizontal movement relatively thereto due to horizontal vibration of the thread holder, means to mount the other end of said weight for both horizontal and vertical free movement relatively to the thread holder due to horizontal and vertical vibration of the latter, and feed means for the traveling surface actuated by both the horizontal and vertical movements of said weight relatively to the thread holder.

5. In a thread holder which vibrates horizontally and vertically during operation of a loom supporting the thread holder, the latter having a ratchet connected to a traveling surface to engage weft ends extending from reserve bobbins in the loom, a weight mounted on the thread holder for free movement relatively thereto in horizontal and vertical directions due to horizontal and vertical vibration of the thread holder, and feed means for the traveling surface actuated by both the horizontal and vertical movements of said weight relatively to the thread holder.

zontal and vertical vibration of the thread holder, and feed pawl means for the ratchet moving with said weight, said pawl means moving the ratchet due to horizontal and vertical movement of said weight relatively to the thread holder.

5 6. In a thread holder having a ratchet connected to a traveling surface to engage weft ends extending from reserve bobbins in a loom operation of which causes horizontal and vertical vibration of the thread holder, a weight mounted on the thread holder for free horizontal and vertical movement relatively to said ratchet due to horizontal and vertical vibration of the thread holder, and two pawls moving with the weight and both engaging the ratchet, one of said pawls moving the ratchet due to horizontal movement of the weight relatively to the thread holder and the other pawl moving the ratchet due to vertical movement of the weight relatively to the thread holder.

10 7. In a thread holder having a ratchet connected to a traveling surface to engage weft ends extending from reserve bobbins in a loom operation of which causes horizontal and vertical vibration of the thread holder, a weight mounted on said thread holder for free horizontal and vertical movement relatively to the ratchet due to horizontal and vertical vibration of the thread holder, and two pawls moving with the weight and both engaging the ratchet, each pawl having a feeding stroke to move said ratchet and a return stroke which is idle relatively to the ratchet, one of said pawls acting as a check to prevent retrograde movement of the ratchet when the other pawl has a return stroke.

15 8. In a thread holder having a ratchet connected to a traveling surface to engage weft ends extending from reserve bobbins in a loom operation of which causes horizontal and vertical vibration of the thread holder, a weight mounted on said thread holder for free horizontal and vertical movement relatively to said ratchet due to horizontal and vertical vibration of the thread holder, and two pawls moving with the weight and both engaging the ratchet for all positions of the weight, each pawl having feeding and return strokes relatively to the ratchet and each pawl serving as a check to prevent retrograde movement of the ratchet when the other pawl has a return stroke.

20 9. In a thread holder having a ratchet connected to a traveling surface to engage weft ends extending from reserve bobbins in a loom operation of which causes horizontal and vertical vibration of the thread holder, a weight mounted on the thread holder for free horizontal and vertical movement relatively to said ratchet due to horizontal and vertical vibration of the thread holder, and two pawls moving with the weight and each having working and return strokes due to movement of the weight relatively to said ratchet, one pawl on a working stroke thereof moving the ratchet when the weight moves horizontally relatively to said ratchet and the other pawl on a working stroke thereof moving the ratchet when the weight moves vertically relatively to said ratchet, one of said pawls acting as a check to prevent retrograde movement of the ratchet when the other pawl has a return stroke.

25 10. In a thread holder having a ratchet connected to a traveling surface to engage weft ends extending from reverse bobbins in a loom operation of which causes horizontal and vertical vibration of the thread holder, a weight having one

end thereof supported by the thread holder for free movement in a horizontal direction relatively to the ratchet due to horizontal vibration of the thread holder, resilient means carried by the thread holder and mounting the other end of the weight for free movement in a vertical direction relatively to the ratchet due to vertical vibration of the thread holder, a pawl connected to said

weight and engaging the ratchet and moving the latter due to horizontal movement of the weight relatively to the ratchet, and a second pawl connected to said other end of the weight and engaging the ratchet and moving the latter due to vertical movement of said other end of the weight relatively to the ratchet.

HERBERT A. WHITIN.
